DESIGN FOR A BROOM RACK

William F. Vernon, Newton, Iowa

Application November 25, 1940, Serial No. 96,785

Term of patent 7 years

To all whom it may concern:

Be it known that I, William F. Vernon, a citizen of the United States and a resident of Newton, in the county of Jasper and State of Iowa, have invented a new, original, and ornamental Design for a Broom Rack, of which the following is a specification, reference being had to the accompanying drawings, forming part thereof.

Fig. 1 is a perspective view of the broom rack, showing my design.

Fig. 2 is a top plan view;
Fig. 3 is a side elevational view; and
Fig. 4 is a front elevational view thereof.

I claim:

The ornamental design for a broom rack, as shown.

WILLIAM F. VERNON.
